William Schuyler
Getting Patent

The Schedule referred to in these Letters Patent and making part of the same containing a description in the words of the said William Schuyler himself of his improvement in the Ash Catcher.

To all whom these presents shall come, Weet known that I, William Schuyler of the County of Philadelphia in the State of Pennsylvania have invented a new and useful Ash catcher for locomotive steam engines and that the following is a full and exact description thereof. Immediately above or near the smoke box of the engine in the smoke pipe of the engine said pipe is made to swell in a conical form until the diameter becomes sufficient to present an area for gauge wire sieve that will pass the draught of the engine without any practicable diminution thereof. The top of said cone terminated in a flange of sufficient projection for screw bolts or other fastenings for the upper part of said pipe hereinafter described. Upon the top of said flange to said cone a wire sieve is placed ^{evenly} fitted in the cone by the exhaust steam pipe which carries off the waste steam of the engine. The wire sieve is secured round the exhaust pipe by a flange projecting ^{upon} from said pipe, which the wire rests and is compressed by an iron ring, screwed down upon the top of said sieve as represented in the drawing, at or fig. 3. Immediately above the wire sieve and the cone in the smoke pipe as here described another cone, similar to the one before mentioned is placed in an inverted position, it which contracts to the ^{inner} diameter of the main bore of the pipe which is fastened to the last mentioned cone as represented in the drawing, at or fig. 4. Upon the outside of the double cone thus formed as above stated in which the gauge wire is placed one or more flues are constructed as represented in the drawing at or fig. 5, with a

door or valve to each as represented at a. & Fig 1.2.3.4. which can be opened or shut at pleasure while the Engine is standing and by which the draught can be regulated, though they are to be shut while the Engine is in motion. On the pipe part of the double cone above described a door is constructed for the purpose of examining, & cleaning the guide cone at pleasure. This door is represented in the drawings at 7. Fig 1.2.8.9. What I claim as my own invention and not previously known in the above described machine is the whole arrangement as herein before described without any connection with any other machine hitherto constructed for the same purpose. I do not confine myself to the exact shape of a round cone for the smoke pipe below the guide cone line. It is for the principles and arrangement hereinbefore described applied in any shape or proportion which I claim to be my improvement.
